UNITED STATES PATENT OFFICE.

DAVID W. BOVEE, OF WATERLOO, IOWA.

APPARATUS FOR THE CONSTRUCTION OF PLASTIC WALLS.

No. 825,183.

Specification of Letters Patent.

Patented July 3, 1906.

Application filed December 16, 1905. Serial No. 292,040.

To all whom it may concern:

Be it known that I, DAVID W. BOVEE, a citizen of the United States, residing at Waterloo, in the county of Blackhawk and State 5 of Iowa, have invented certain new and useful Improvements in Apparatus for the Construction of Plastic Walls, of which the following is a specification, reference being had therein to the accompanying drawings.

10 My invention relates to improvements in apparatus for the construction of plastic walls.

The object of my invention is to provide means for supporting the mold-sections in the 15 construction of walls, and pertains particularly to means for independently supporting and adjusting the mold-sections from the outside, so that the said means does not interfere in the filling in between the mold-sections and the backing. By this structure it 20 will be readily seen that the usual means extending from the backing across the mold to the mold-sections is dispensed with, thus obviating great trouble experienced in removing said means from the completed wall after 25 it has hardened.

Another object of my invention is to provide means whereby the whole frame carrying the separate adjusting means is drawn 30 inward should the pressure of the cement tend to bulge the same outward.

A still further object of my invention is to provide a more simple, cheap, and effective means for independently or jointly adjusting the front of the mold-sections from the outside. 35

In the accompanying drawings, Figure 1 is a side elevation of a section of wall under construction, showing the section-adjusting means. Fig. 2 is a vertical sectional view 40 taken on the line $x-x$ of Fig. 1. Fig. 3 is an enlarged perspective view of the framework on the outside of the mold-sections for holding the same. Fig. 4 is an enlarged perspective view of the joint between the mold-sections. 45

Referring now to the drawings, 1 represents a backing for the concrete wall, which, as shown, is preferably constructed of vertically-disposed timbers 2, having their inner faces covered by two-inch plankings 3, placed close together to form a solid backing for the wall. The said backing is held in a vertical position in any desired manner. Usually in 55 constructing walls of this character the mold-

sections are held to the backing by means of bolts or the like passing across the space between the backing and the mold-sections, so that these bolts interfere with the filling in of the cement and also are left within the wall 60 and removed after the mold-sections are removed, which in many cases is difficult and which is also objectionable because it leaves openings in the wall. In my invention, as before stated, the usual backing is used, and 65 I provide a framework adjacent thereto, and said framework is composed of vertically-arranged timbers 4, which have secured thereto at predetermined distances horizontally-arranged cross-bars 5, which, as shown, are on the inside of the vertical timbers. The said horizontally-arranged bars are provided throughout their entire length with the horizontally-arranged slots 6. Between the said framework and the backing are arranged the 70 mold-sections 7, which, as is understood, are usually of the same width in constructing a building, and thus the joints between the upper and lower edges of the mold-sections are 75 always the same distance apart. Thus the 80 horizontally-arranged slotted bars 5 are arranged the same distance apart on the upright 4, so that the slots 6 are at all times opposite the joint between the upper and lower faces of the mold-sections, the purpose of 85 which I will now proceed to describe.

The mold-sections, as shown, are of different lengths, and this is necessary in building between windows or ending up a wall at the corner, as illustrated at the left of Fig. 1. 90 Should the regular length section be too long to fill the space, a shorter section is used, and thus sections of all lengths are necessary. The corners of each mold-section are cut away at 8, and passing through the opening 95 formed by the two cut-away portions of the abutting corners of the sections are bolts 9, which have their heads 10 abutting the inner faces of the mold-sections. The said bolts are screw-threaded throughout their entire 100 length, and each bolt on the outside of the mold-sections is provided with a nut 11, by means of which the mold-sections are clamped between the same and the head of the bolt for holding the sections together. The said bolts 105 extend outward through the slot 6 in the horizontal bar 5, and on the inside thereof are provided with nuts 12 and on the outside by nuts 13. The said bars 5, as shown, are a distance from the mold-sections, and by the ad- 110

justment of the nuts 12 and 13 the mold-sections are adjusted in or out, as desired, to bring all of them in a vertical alinement.

The bolts 9 passing through the slots 6 in the members 5, it will be seen that the bolts may be arranged in or at any point along the same that a joint between the mold-sections occurs, and thus when using the smaller mold-sections the bolts are easily used or adjusted. The standards 4 opposite each of the slots 6 of the horizontal bars are provided with the openings 14, so that the adjusting-bolts 9 may pass therethrough when the joint of the mold-sections comes directly under the said standard. In such a case it is understood that a longer bolt is used, but the operation is precisely the same.

The mold-sections, as shown in Fig. 4, are provided on two sides with the overlapping flange 15, which extends over the two abutting sides of the adjoining sections which are not provided with the flanges, and thus the joints between the sections are closed by the flange and the cement is prevented from passing between the same.

In using mold-sections of this character the pressure of the cement placed between the backing and the mold-sections moves the framing slightly out of alinement, and in order to prevent this and also to straighten the said framework, should such occur, I provide transverse tie rods or wires 16, which pass through the planking and uprights of the backing and are secured thereto in any desired manner. The said tie rods or wires pass across the space 17 to be filled with cement and through the elongated slot 6 of the cross-bar 5 and through one of the openings 14 in the standard 4. The said standard is provided with a U-shaped truss-plate 18, which is rigidly secured thereto and provided with a hooked bolt 19 passing therethrough and provided at its inner end with the hook 20, which engages a loop 21 in the tie rod or wire 16. Said bolt on the outside of the truss-plate 18 is provided with a nut which by turning draws the bolt 19 outward and tightens the tie rod or wire 16. It will be seen that these bolts or wires are arranged at the top and bottom of the frame, and should the pressure of the cement tend to force the mold-sections and the framework outward the tie-rods are tightened, holding the sections in their proper position. It is also understood that the mold-sections are removed after the cement is hard, and the framework is also moved upward, while the tie-rods are left in the wall and cut off, and, as before stated, the horizontal bars when raised are always in an alinement with the abutting horizontal edge of the mold-sections.

Having thus described my invention, what I claim, and desire to secure by Letters Patent, is—

1. An apparatus of the character described

comprising a backing, a framework adjacent thereto and having horizontal slots therein, mold-sections between the framework and backing, and bolts adjustably secured within said slots and passing between the mold-sections, and means carried by the bolts for locking said mold-sections together. 70

2. An apparatus of the character described, comprising a backing, a framework adjacent thereto, mold-sections between the framework and backing, bolts carried by the framework, and means carried by the bolts for locking said mold-sections together. 75

3. An apparatus of the character described, comprising a backing, a framework adjacent thereto, mold-sections between the backing and framework, and means carried by the framework for independently adjustably holding the mold-sections to the framework and locking the sections together independent of the locking means. 80

4. An apparatus of the character described, comprising a backing, a framework adjacent thereto, mold-sections between the backing and framework, and means carried by the framework for independently adjusting the mold-sections to or from the frame and locking the sections together independent of the locking means. 85

5. An apparatus of the character described, comprising a backing, a framework adjacent thereto, mold-sections independently adjustably secured to the framework, and tie-rods for adjusting the framework to or from the backing. 95

6. An apparatus of the character described, comprising a backing, a framework adjacent thereto, mold-sections independently adjustably secured to the framework, tie-rods carried by the framework and adjustably secured to the framework for drawing the framework toward the backing. 105

7. An apparatus of the character described, comprising a backing, a framework adjacent thereto, mold-sections independently adjustably secured to the framework, tie-rods secured to the backing and, through the mold-sections and the framework, and brackets carried by the outside of the framework, and hooked bolts adjustably secured within the brackets and interlocked with the ends of the tie-rods for drawing the framework toward the backing. 110

8. An apparatus of the character described, comprising a backing, a framework adjacent thereto, mold-sections between the backing and framework, bolts adjustably secured to the framework and passing between the mold-sections, and a nut on the outside of the mold-sections for clamping the mold-sections between the nut and the head of the bolt. 120

9. An apparatus of the character described, comprising a backing, a framework adjacent thereto, mold-sections between the backing and the framework, the corners of said sec- 125

tions being broken away, and bolts adjustably secured to the framework and passing through the broken-away portions of the corners with the heads on the inner side, and 5 nuts on said bolts on the outside of the mold-sections for clamping the sections together.

10. An apparatus of the character described, comprising a solid backing, a framework adjacent thereto, tie-rods securing the 10 backing and frame together, mold-sections intermediate the frame and backing, bolts longitudinally and horizontally adjustably mounted within said frame, means for removably securing bolts to the mold-sections, 15 whereby the mold-sections are secured together and adjustably secured to the frame.

11. An apparatus of the character described, comprising a backing, a frame arranged adjacent thereto and composed of vertically-arranged beams carrying on their inner face horizontally-arranged strips having elongated slots therein, tie-rods securing the frame in its adjusted position to the backing, 20 mold-sections intermediate the backing and frame, bolts passing the slots in the frame and horizontally and longitudinally adjustable therein, and means carried by the inner ends 25

of said bolts for securing the mold-sections thereto and securing the said sections together.

12. An apparatus, of the character described, comprising a backing, a frame arranged adjacent thereto and composed of vertically-arranged beams carrying on their inner faces horizontally-arranged strips having elongated horizontal slots therein, tie-rods 30 securing the frame in its adjusted position to the backing, mold-sections intermediate the backing and frame, bolts passing through the slots in the frame and horizontally and longitudinally adjustable therein, the vertical beams opposite the slots having a series of horizontally-arranged openings to receive the bolts when a joint of a mold-section is opposite the same, and means carried by the inner 35 ends of said bolts for securing the mold-sections to the frame and the sections together.

In testimony whereof I affix my signature in presence of two witnesses.
